Specification of Letters Patent. Patented Aug. 27, 1912.

Application filed March 17, 1905, Serial No. 250,634. Renewed July 2, 1909. Serial No. 505,625.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and has for its object the improvement of such systems by the combination in operation of the best features of so-called manual systems with the best features of the so-called automatic systems.

According to past practice, prior to my invention, the best and most widely used form of manual system has been that known as the straight multiple, wherein the switch-board or boards for the interconnection of subscribers have been provided with an answering jack for each line, and with multiple jacks for all the lines duplicated upon each section or within reach of each operator. The number of multiple jacks in such a system is very large in proportion to the number of lines, and in a large exchange serving many subscribers gives rise to many difficulties, mechanical, electrical, and financial. On the other hand, the best and most widely known form of automatic system has been one provided with an automatic switch or first selector for each line, and auxiliary switches controlled by the first selector switches, some or all of which have been provided with multiple contacts for the various subscribers' lines.

The most expensive and generally objectionable part of a multiple manual system 40 is that embodied in the multiple jacks. The most expensive and generally objectionable feature of the automatic system mentioned has been and is the necessity for a first selector switch for each line. The auxiliary switches in the automatic system, and the answering jacks and signals in the manual system, are unobjectionable. Hence I eliminate the other features, and combine these. In so doing, I employ operators, who, having only a fraction of the work to perform which is required of them in the regular manual system, can handle a great many more lines per operator, so that only a few operators are required. I effect very large

savings by this arrangement, as well as a 55 positive gain in efficiency, and many incidental advantages which will sufficiently appear from the following description.

Briefly stated, my invention comprehends a manual switchboard or boards provided 60 with a line terminal and calling signal for each line, and cord circuits whereby the operators may answer the subscribers' calls by plugging them through to the regular first or other selector switches. The subscribers are provided with the regular automatic sender or transmitter, and so far as they are concerned the system is full automatic. The operators have substantially 65 nothing to do but stick plugs, and as the number of automatic switches required is 70 only about thirty per cent. of the number in the full automatic systems, the chances of trouble, and the difficulties usually met in locating the same are correspondingly 75 reduced.

My invention is illustrated in the accompanying drawings, wherein—

Figure 1 shows a subscriber's station and a portion of the central office circuits, including an operator's cord circuit. Fig. 2 is a diagram of successive link conductors and switches in the automatic portion of the system. Fig. 3 is a diagram similar to Fig. 1, showing a modification; and Fig. 4 85 is a diagram of a further preferred modification.

Referring to Figs. 1 and 2, I have shown the simplest conception of my invention as applied to the Strowger automatic system. Between the dotted lines 100 and 200, Fig. 1, I have shown interposed the necessary apparatus to form the connecting link between the subscriber's station and the ordinary first selector switch. This apparatus 90 does not change the operation of the rest of the system, which remains the same throughout. This interposed apparatus 95 consists of a line jack and an annunciator drop at which the subscriber's line terminates, the trunk jack and busy lamp to which the first connector switch is terminated and the cord-circuit used to connect the line-jack with the trunk-jack and thus 100 complete the circuit. At the subscriber's station A the regular Strowger instrument 105 is shown, in addition to which is added a hand generator G. The line-wires 1 and 2

terminate in the central office on the jack J. To the inner contact j^2 and to the wire 1 there is connected the annunciator-drop M, and to contact j^4 there are connected private 5 normal multiples leading to the connector switches. The contact j^3 is grounded. The cord-circuit consists of the answering-plug P, with a tip p normally connected to generator G, through the contacts k^4 , k^5 , with 10 the latch magnet S in series. The tip p of the calling-plug P' is connected to the inner contact k^3 . The sleeve p^a of the answering-plug p is connected to the opposite side of the generator G, through the contacts k' 15 and k^2 . The sleeve p' of P' is connected to the contact k. These contacts are controlled by the latch s of the magnet S. The third conductor p^2 of the calling-plug P' is grounded. The first selector-switch is 20 connected to the springs j^5 and j^6 of the trunk-jack J' by the wires 10 and 11. The busy lamps s^2 are connected to battery B by the wire 13.

The first selector switch Z, the second 25 selector switch Z' and the connector switch Z² being of the well known Strowger type and no part of my present invention, I will not describe them in detail. The first selector switch Z has a vertical relay S⁶, a rotary 30 relay S⁷, a vertical magnet s⁸, a rotary magnet s⁷, a back release relay X, a private relay S⁹ and a release magnet W. The trunk wipers z' and z² and the private wiper z³ are mounted on the spindle z. The 35 second selector Z' Fig. 2, consists of the vertical relay S⁹, rotary relay S¹⁰, vertical magnet s⁹, rotary magnet s¹⁰, back release relay X', private relay S¹¹, and the release magnet W'. The trunk wipers z⁵ and z⁶ 40 and the private wiper z⁷ are mounted on the spindle z⁴.

The connector switch Z², Fig. 2, consists of the vertical relay S¹², rotary relay S¹³, vertical magnet s¹², rotary magnet s¹³, private 45 relay S⁴, back signal relays W³, W⁴, ringing relay Y and release magnet W². The trunk wipers z⁹ and z¹⁰ and the private wiper z¹¹ are mounted on the spindle z⁸. The wires 18 and 20, 19 and 21 are separated 50 by the condensers C and C', respectively. These switches are shown in patents issued March 13, 1906, to Keith and Erickson Nos. 815,176 and 815,321.

The operation of this system is as follows: The subscriber signals by turning his hand generator G, which throws the drop annunciator M at the central office through the contacts j^2 , j^4 . The operator perceiving the signal inserts the answering-plug P into 55 the jack J, and the calling plug P' into any trunk jack J' which does not show a busy signal, preferably the latter first. This opens the contacts j^1 , j^2 , disconnects the line-annunciator M, also grounds private normal 60 multiple. As soon as this connection is

made, generator current is sent out on the subscriber's line with the relay S, in series. The armature s' is then attracted and releases the latch s. This release disconnects the generator G by breaking the contact k' , k^2 , k^4 and k^5 , and at the same time closes the contacts k , k' and k^3 , k^4 . The tip p of the answering-plug P, and the tip p' of the calling plug P' are now connected as are the sleeve p' of the answering-plug P and the sleeve p' of the calling-plug P'. This completes the connection between the subscriber's instrument and the first selector switch Z, and at the same time lights the busy lamp s^2 and its multiple in each position. The current from generator G on the subscriber's line when the connection is made serves to advise him that the connection is completed so that he can operate his dial. When ordinary generator current is employed, it may manifest itself to the subscriber as an audible buzz or may operate any desired form of signal. Upon operating his dial the subscriber makes and breaks the ground on the vertical side of the line, these makes and breaks corresponding to the thousands numeral of the number with which he desires to be connected. These makes and breaks or impulses actuate the vertical relay S⁶ in the first selector switch Z, by way of line-wire 1, strands 6 and 8 in the cord-circuit, wire 10, leading to the trunk-jack J'. After the last impulse has come in over the vertical side of the line, one impulse is sent in over the rotary side 95 of the line and moves the side switch one step, which cuts on the rotary magnet s⁷. The actuating of this relay S⁶ causes the spindle Z, carrying the wipers, to step up to the desired row. The rotary magnet s⁷ 100 now being cut on, the spindle Z begins to rotate and continues to rotate until the wiper z³ finds a contact in the private normal which has no ground, that is to say not busy. At the first step of the side switch, the private relay S⁸ is placed in connection with wiper z³, with the relay X, in series. This relay S⁸ continues to hold up so long as the wiper z³ finds a grounded contact. The instant a free contact is found, that is 110 an idle one, the relay S⁸ becomes deenergized, causing the side switch to make a second step which cuts off the rotary magnets s⁷, grounds the wiper z³ through the windings of relay X, disconnects the vertical and rotary relays S⁶ and S⁷ and connects the trunk-wires 10 and 11 to the wires 12 and 13, leading to the wipers z' and z². The subscriber's station is now in connection with the contacts leading to the thousand group of the party he desires to be connected with. The second movement of his dial sending in impulses over the vertical side of the line corresponding to the hundred numeral of the party he wishes to 125 130

be connected with, actuates the vertical relay S^9 of the second selector switch Z' , Fig. 2.

After the last impulse has come in over the vertical side of the line, one impulse is sent in over the rotary side of line which causes the side switch to make one step. This cuts on the rotary magnet s^{10} and connects the private relay S^{11} to the private wiper z^1 , with the back release magnet X' , in series. The actuating of this vertical relay S^9 causes the spindle z^4 , carrying the wipers, to step up to the desired row. The rotary magnet s^{10} being cut on, the spindle now begins to rotate and continues to rotate until the wiper z^7 finds an idle contact. The private relay S^{11} , connected to the wiper z^1 , through the relay X' , in series, continues to attract its armature cutting off the vertical magnet s^9 so long as the wiper z^7 finds a busy or grounded contact. The instant it finds an idle contact the relay S^{11} becomes deenergized. This causes the side switch to make one more step, which cuts off the rotary magnet s^{10} , grounds the wiper z^7 through the winding of relay X' , disconnects the vertical and rotary relays S^9 and S^{10} and connects the trunk-wires 14 and 15 to the wires 16 and 17, respectively, leading to the wipers z^5 and z^6 . The relay X of the first selector switch Z and the relay X' of the second selector switch Z' are low-wound and will not operate in series with the relays S^8 and S^{11} , respectively. The subscriber is now connected over the vertical side of the line by the line 1, strands 6 and 8 of the cord-circuit, wires 10 and 12 and wiper z^1 , selector switch Z , wires 14 and 16 to the wiper z^5 of the second selector switch Z' , over the rotary side of the line by the line 2, strands 7 and 9 of the cord-circuit, wires 11 and 13 and the wiper z^2 of the first selector switch Z , wires 15 and 17 to the wiper z^6 of the second selector switch Z' . The subscriber in making the third movement of his dial selects the ten numeral of the number of the subscriber with whom he desires to be connected. The impulses corresponding to the number of the ten numeral wanted, coming in over the vertical side of the line actuate the vertical relay S^{12} , which in turn operates the vertical magnet s^{12} and causes the spindle carrying the wipers to step up to the desired row. After the last impulse has come in over the vertical side of the line, one impulse is sent in over the rotary side of the line, which makes the side switch take one step. This cuts off the vertical magnet s^{12} through the normally closed contacts of the private relay S^{14} . It also connects the release magnet W^2 to the wiper z^{11} , through the normally open contacts of the private relay S^{14} . The subscriber is now connected to contacts leading to the ten group of the line he desires.

The fourth and last movement of his dial

sends in impulses over the vertical side of the line corresponding to the unit of the line he wishes to be connected with. These impulses actuate the vertical relay S^{12} , which in turn operates the rotary magnet s^{13} , through the normally closed contacts of relay S^{14} . This causes the spindle z^8 , carrying the wipers, to rotate and places the wipers z^9 and z^{10} in connection with the line desired. After the last impulse has come in over the vertical side of the line, one impulse comes in over the rotary side of the line, which causes the side switch of the connector switch Z^2 to make one more step. This cuts off the rotary magnet s^{18} and connects the ringing relay Y in its place, grounds the wiper z^{11} and closes wires 22 and 24 to the wiper z^9 and wires 23 and 25 to the wiper z^{10} . The calling-subscriber is now connected straight through to the line of the party called for. He now pushes his ringing button which places a ground on the vertical side of the line. This operates the relay S^{12} , which in turn operates the ringing relay Y through the normally closed contacts of the relay S^{14} . The relay Y while energized for ringing, disconnects the wires 20, 22, 21 and 23 to prevent generator current flowing back to the calling subscriber's station. At the end of the conversation, the subscriber in hanging up his telephone places a passing ground on both sides of the line simultaneously, which causes the relays S^{12} , S^{13} , in the connector switch Z^2 , Fig. 2, to become energized and attract their armatures at the same time. This places the windings of the release magnet W^2 and the back release magnet X' , in series, one terminal of the winding X' being grounded and one terminal of the winding of magnet W^2 being connected to battery. Both relays will thereupon become energized, the release magnet W^2 restoring all the parts of the connector switch Z^2 to their normal position, the relay X' closing the circuit of the release magnet W^2 and the back release magnet X , in series. The magnet W^2 restores all the parts of the second selector switch Z' to their normal position. The back release relay X closes the circuit of the release magnet W , by way of 30, 31, 32, 33, 34, to battery, the magnet becomes energized and in turn restores all the parts of the first selector switch Z , Fig. 1, to their normal position. The calling-subscriber in addition to hanging up his telephone at the end of the conversation must turn his hand generator, which throws the clearing-out drop connected across the strands 8 and 9 of the cord-circuit, a condenser being in series so as not to interfere with the impulses necessary in operating the selector and connector switches. The operator upon getting this disconnect signal withdraws both plugs, which extinguishes the busy lamp s^2 and its multiple in each

position. The latch s' is restored to its normal position, which bridges the generator across the answering-plug P ready to be used for the next call.

5 Relays W^3 and W^4 are extra release relays controlled by the called subscriber, in order to prevent the possibility of some one calling him and then maliciously keeping his line busy against his will. When the called 10 subscriber hangs up his receiver he momentarily grounds both wires 20 and 21, energizing both relays W^3 and W^4 , and thereby closing the circuit of release magnet W^2 .

15 In Fig. 3, I have shown a modification of this system. In Fig. 4, I have gone a step farther and have shown the system in operation with a common battery for signaling purposes and a local battery for talking.

20 The first selector switch Z , Fig. 1, and the second selector switch Z' and connector switch Z^2 , Fig. 2, are used in connection with systems shown in Figs. 3 and 4 and are not duplicated, as their action is the same

25 in connection with each system. The modification in Fig. 3 consists of having a cut-off relay in the line-circuit to disconnect the line-drop, instead of depending upon breaking the contacts in the jacks. A supervisory

30 lamp with its controlling relays is added to the cord-circuit and the subscriber need not operate his hand generator for a disconnect signal, the whole operation being automatic. In the trunk-circuit instead of having the 35 busy lamps lighted through the third conductor of the calling-plug direct, I have substituted a relay which when energized causes the busy lamp to glow.

Referring now to Fig. 3, A is a subscriber's station, equipped with the regular 40 Strowger instrument, to which in addition to the other apparatus there is added a hand generator G . The line-wires 1 and 2 leading from station A terminate in the central

45 office in jacks J . The line apparatus at central consists of the drop or annunciator M connected to the line through the front contacts n and n' of the cut-off relay N . The cut-off relay N is connected to the ring j^2

50 of the jack J . To the ring j^2 there is also connected the private normal multiple f leading to the automatic switches. The cord-circuit consists of the answering-plug P with the tip p connected to the tip p' of the calling-plug P' by the strand 3 through the contact springs k^2, k^4 of the ringing key K .

55 The sleeve p' of the answering plug P is connected to the sleeve p' of the calling-plug P' by the strand 4, through the contacts k^8 and k^6 of the ringing key K . The windings of the relays S, S' , respectively,

60 are connected to the strands 3 and 4 and to battery B by the wire 7. To the third conductor p^8 of the answering-plug P is connected the relay S^2 to ground. A locking or

supervisory relay S^3 , of which one terminal of the winding is connected to battery and the other terminal to the contact s^{14} of the relay S controls the lamp s and is itself in turn controlled jointly by the relays S and S' . The generator G is connected to the back contacts k and k' of the ringing key K . The third conductor p^2 of the calling plug P' is grounded. The first selector is connected to the jack J' , multiplied in each position by the wires 10 and 11. These jacks have an associate busy lamp s^2 controlled by the relay S^4 , which is connected to the ring j^2 of the jack J' .

The operation of my system is as follows: 80

The subscriber signals by turning his hand generator G , which throws the drop M at the central office through the contacts n and n' of the cut-off relay N . The operator perceiving the signal inserts the answering-plug P , into the jack J . Current then passes through the windings of the cut-off relay N and the relay S^2 , which causes their armatures to attract. This cut-off relay N disconnects the drop M , and the relay S^2 places ground on the back contact s^8 of the relay S^3 . Ground is also placed on the private normal multiple f , which makes it busy for outgoing calls. The operator instead of asking for the number inserts the calling-plug P' into any trunk-jack J' which does not show a busy signal. The insertion of the calling-plug P' into the trunk-jack causes current to flow through the relay S^4 . The relay S^4 then attracts its armature and 90 lights the lamp s^2 and its multiple in each position, which serves as a busy signal for the other operators. Immediately after the completion of this connection, generator current or a busy back signal of some description is sent back over the calling line by the contacts k^4, k^5 of the ringing key K coming into contact with the generator terminals k and k' , either automatically or by the operator moving the lever. The generator current is prevented flowing over the calling-plug P' by the breaking of the contacts k^2 and k^3 . The subscriber upon receiving the 100 back signal knows that the connection is completed and thereupon moves his dial in the regular manner and gets his party by way of the cord-circuit and through the trunk to the selector and connector switches in the regular manner. The relays S and S' are in parallel with the vertical and rotary 110 relays in the automatic switches, and while they respond to the impulses of the transmitter at the subscriber's instrument, they do not interfere with the working of these automatic switches. At the end of the conversation, the subscriber hanging up his 120 telephone places a passing ground on each side of the line simultaneously. This restores the automatic switches to their normal position. This passing ground also 130

105

110

115

120

125

130

causes current to flow through the two relays S and S' at the same instant, which attracts their armatures. The attraction of these armatures at the same time passes current through the relay S³ which has its winding in series with the contacts s¹⁴ and s¹⁵ of the relays S and S' to battery. The relay S³ then attracts its armature, lights the supervisory lamp s and remains locked through the contact s⁹, on which ground is placed by the relay S². The operator upon receiving the disconnect signal withdraws both plugs, relay S² being disconnected, its armature falls back, removes the ground from the contact s⁹ and releases the relay S³, which in turn extinguishes the lamp s. The relay S⁴ also being disconnected, extinguishes the lamp s² and its multiple in each position.

Referring now to Fig. 4, a central signal system is shown, that is, the common battery is used for signaling purposes and local battery used at the subscriber's station for talking. At the subscriber's station is shown the regular Strowger instrument, which in addition to the other apparatus has a condenser C placed in series with the ringer. There is also a lock-out relay F. This relay is for the purpose of preventing the subscriber from using his dial until the connection has been completed or the signal answered at the central office. To fulfil the first condition, that is to prevent the subscriber from operating his dial until the full connection is completed, the lock-out relay F would have its armature f provided with a two-step escapement. The first step would be made when the operator inserted the answering-plug and connected the generator across the line. The second step would be made when the connection was completed and the generator current disconnected. To provide for the second condition and have the armature f make but one step, the dial would be released when the operator first answered and the connection must be completed before the subscriber has time to operate his dial. The line-wires 1 and 2 leading from the subscriber's station terminate in the central office and jack J. The line apparatus at central consists of the line-relay M which controls the lamp m and is connected to the line through the contacts n, n', and n², n³ of the cut-off relay N. The relay N is connected to the ring j² of the jack J. The private normal multiples f are also connected to the ring j². The cord-circuit consists of the answering-plug P, with a tip p connected to the tip of the calling plug P' by the strand 3 through the contacts s⁴ and s⁵ of relay S². The sleeve p' of the answering-plug P is connected to the sleeve p' of the calling-plug P' by the strand 4, through the contacts s⁶ and s⁷ of the relay S². The windings of the relays S and S', respec-

tively, are connected to the strands 3 and 4 and to battery by the wire 7. The relay S² is connected to the third conductor p² of the answering-plug P by the wire 10, contacts s⁸, s⁹ and the wire 9. One terminal of the winding of the relay S⁵ is connected to the third conductor p² of the calling-plug P', the other terminal being grounded. A locking or supervisory relay S³ is controlled jointly by the relays S and S', one terminal of the winding being connected to battery and the other in series with the contacts s¹⁴ and s¹⁵. The supervisory lamp s is controlled jointly by the relays S³ and S⁵.

The operation of my system is as follows: The subscriber signals by removing his telephone which closes the circuit of the line-relay M through the contacts n, n', n² and n³ of the cut-off relay N, which then attracts its armature, closes the contacts m' and m² and lights the line lamp m. The operator perceiving the signal inserts the answering-plug P into the jack J, which causes current to flow through the windings of the cut-off relay N and the relay S² in series, which causes their armatures to attract. The relay N disconnects the line-relay M, which in turn extinguishes the line-lamp m. The relay S² attracting its armatures places generator current across the answering-plug P to the contacts s⁸, s⁴, s⁵ and s⁶. It will be noticed that the winding of the relay S² is connected to the third conductor p² of the answering-plug P, through the contacts s⁸ and s⁹ of the relay S⁵. The operator at once inserts the calling-plug P' into a trunk-jack J', which does not show a busy signal. The insertion of this plug causes current to flow through the windings of the relays S⁴ and S⁵, in series, causing their armatures to attract. The relay S⁴ attracting its armature causes the busy lamp s² and its multiple in each position to glow. The relay S⁵ attracting its armature, disconnects the relay S² by breaking the contacts s⁸ and s⁹. The third conductor p² of the answering-plug P instead of being connected to ground through the winding of the relay S² is connected to ground by the contacts s⁹ and s¹¹ to keep the cut-off relay energized. The attraction of the armature of the relay S⁵ places a ground on the contact s¹⁶ of the relay S³, through the contacts s⁹ and s¹⁰. The moment the relay S² is disconnected by the relay S⁵, upon the insertion of the calling-plug P' into the jack J', the generator was disconnected from the answering-plug P. The subscriber is then at liberty to operate his dial. He operates his dial in the regular manner and gets his party by way of the cord-circuit and through the trunk to the selector and connector switches in the regular order. The relays S and S' as in Fig. 3 are in parallel with the vertical and rotary relays, and while they respond to

the impulses of the transmitter at the subscriber's instrument they do not interfere with the workings of these automatic switches. At the end of the conversation, 5 as before described, a passing ground is placed on both sides of the line simultaneously, when the subscriber hangs up his telephone. This restores the automatic switches to their normal position. This passing ground also causes current to flow through the two relays S and S' at the same instant, which attracts their armatures. The attraction of these armatures at the same time passes current through the relay 10 S³, which has its winding in series with the contacts s¹⁴ and s¹⁵ of the relays S and S' to battery. The relay S³ then attracts its armatures, lights the supervisory lamp s and remains locked through the contacts s¹⁶, 15 s¹⁷, s⁹, s¹⁰ and s¹¹ to ground. The operator upon receiving the disconnect signal withdraws both plugs, the relay S⁵ being disconnected, its armature falls back, removes the ground from the contact s¹⁸ of 20 the relay S³ which thereupon releases and extinguishes the lamp s. The relay S⁴ being disconnected, extinguishes the lamp s² and its multiple in each position. The cut-off relay N being disconnected lets its 25 armatures fall back and again connects the line-relay M across the line-wires 1 and 2.

Having thus described my invention, what I claim and desire to secure by Letters Patent is:

35 1. In a telephone exchange system a plurality of subscribers' lines, a number of first selector switches less than the number of subscribers' lines, means manually controlled for bringing said first selector switches into connection with calling lines, together with means whereby the said selector switches may then be controlled by the subscribers to select the lines wanted, and to restore the switches after use, and signal 40 devices connected with the manual portion of the apparatus to indicate to the operators the necessity for connection and disconnection, substantially as described.

2. In a telephone exchange system a plurality of subscribers' lines, a number of first selector switches less than the number of subscribers' lines, operators' cord-circuits for connecting said first selector switches with the calling lines, together with sending 45 devices, at the substations, and responsive devices at the central station whereby the said selector switches may then be controlled by the subscribers to select the lines wanted, and to restore the switches after use, line- 50 annunciators and clearing-out annunciators connected with the lines and cords, respectively, to indicate to the operators the desire of the respective subscribers for connection and disconnection, substantially as de- 55 scribed.

3. In a telephone exchange system a plurality of subscribers' lines terminating upon spring-jacks, a line-signal associated with each jack and controlled from the subscriber's station, a plurality of first selector switches less in number than the number of lines, operators' connective circuits with answering plugs and means to connect a calling line therethrough with an idle first selector switch, a clearing-out signal associated with said answering plug, auxiliary switches containing line-terminals and cooperating with the first selector switches, and sending devices at the subscribers' stations whereby after a connection is manually initiated in response to a call, the calling subscriber may thereafter complete the connection through the automatic switches and at the end of the conversation may restore the same, substantially as described. 70 75 80 85

4. In a telephone exchange system a plurality of subscribers' lines terminating at a manual switchboard, with associated signal devices whereby a calling line may attract the attention of an operator, a number of first-selector automatic switches less than the number of lines, auxiliary switches associated therewith and containing multiple-terminals for the lines, operators' connective means and terminal devices for the selector switch circuits upon the manual switchboard manually controlled to connect a calling line with an idle first selector switch, means thereafter controlled by the subscribers for setting and releasing the 90 95 switches, and clearing-out signals associated with the operators' circuits to indicate the desire of connected subscribers of disconnection, substantially as described. 100

5. In a telephone exchange system a plurality of subscribers' lines, manual connective terminals therefor, signal devices associated therewith and becoming active in response to subscribers' calls, automatic switches containing terminals of the same 110 lines, operators' connective circuits for connecting a calling line with an idle switch, means controlled by the subscribers for setting and releasing the switches, and clearing-out signals connected with said connective circuits, substantially as described. 115

6. In a telephone exchange system, subscribers' lines with manual connective circuits and automatic switches for interconnecting them, each line having an answering terminal manually accessible only, and one or more calling terminals in the automatic switches only, said switches being subdivided into classes and groups, certain groups in each class containing multiple terminals for switches of the next class, and the switches of the last class containing the said line terminals, said manual connective circuits adapted to initiate connection between lines through the successive classes, 120 125 130

and means whereby the continuity of a connection may thereafter be controlled by the subscribers, substantially as described.

7. In a telephone exchange system, subscribers' lines having manually accessible answering terminals, and automatically accessible calling terminals, two or more sets of link or trunk-circuits each containing an automatic switch adapted to be successively 10 operated to reach said calling terminals, together with operators' cord-circuits for interconnecting the first set of links or trunks with calling subscribers' lines, and means controlled by the subscribers for setting and 15 releasing said switches, substantially as described.

8. In a telephone exchange system, a plurality of subscribers' lines, first selector switches in number less than the number of 20 lines, means whereby said switches may be manually switched to be brought under control of calling lines, becoming thereby individual line switches for the time being, as to both setting and releasing, and auxiliary 25 switches in groups containing the terminals of the same lines, together with connections from said auxiliary switches brought to and controllable by and through the first selector switches, substantially as described.

30 9. In a telephone exchange system, a plurality of subscribers' lines, first selector switches in number less than the number of lines, means whereby said switches may be manually switched to be brought under con-

trol of calling lines, becoming thereby individual line switches for the time being, and auxiliary switches in groups containing the terminals of corresponding groups of trunks, connector switches connected thereto, and containing terminals of the same subscribers' lines in groups, and means whereby the said switches may be controlled through the trunks and their accompanying circuits to reach the wanted subscribers' lines, and for purposes of restoration to normal, substantially as described. 35 40 45

10. The combination in a telephone system of subscribers' lines, a manual switchboard and automatic switches containing respectively answering and calling terminals 50 for said lines, and operators' cord-circuits for interconnecting the calling lines and switches, together with means controlled by the subscribers for both setting and releasing said switches, substantially as described. 55

11. A semi-automatic telephone exchange trunking system provided with selectors and connectors responsive to a calling subscriber, and means by which an operator connects a selector with the line of the calling subscriber before the call can be extended in the direction of the called subscriber. 60

In testimony whereof I have affixed my signature in presence of two witnesses.

EDWARD E. CLEMENT.
